UNITED STATES PATENT OFFICE.

JOHN R. ROGERS, OF BROOKLYN, NEW YORK, ASSIGNOR TO MERGENTHALER LINOTYPE COMPANY, A CORPORATION OF NEW YORK.

LINOTYPE-MACHINE.

No. 890,177.

Specification of Letters Patent. Patented June 9, 1908.

Application filed January 14, 1908. Serial No. 410,734.

To all whom it may concern:

Be it known that I, JOHN R. ROGERS, of 5
borough of Brooklyn, county of Kings, and
State of New York, have invented a new and
useful Improvement in Linotype-Machines,
of which the following is a specification.

My invention has reference to machines
wherein a composed line of matrices is pre-
sented momentarily to close the face of a
10 slotted mold in order to form type characters
on the edge of a metal slug cast therein, as
shown for example in U. S. Letters Patent to
Mergenthaler, No. 436,531. In these ma-
chines, the mold stands in a horizontal pos-
15 ition during the casting action, and it is
necessary that the matrices, presented edge-
wise to the mold, shall be adjusted and
aligned vertically with great accuracy, in
order that their characters may appear in
20 the proper positions on the edge of the slug.
This alinement is secured by means of one
or more horizontal ribs or shoulders lying
parallel with the mold slot and engaging ears
in the lower ends of the matrices, which are
25 forced into close contact therewith. It is
the common practice to use with the one
mold, different fonts or sets of matrices, hav-
ing characters of different sizes. It is also
30 the common practice to make the mold
adjustable in such manner that the thick-
ness of the slug may be varied at will. For
these reasons, and in order to insure the
proper location of the matrix characters
35 with reference to the mold under all circum-
stances, it is usual to form the alining rib or
ribs on a separate plate, known as the keeper-
plate, secured to the mold in such manner
40 that it may be adjusted vertically or replaced
by another plate having its alining shoulder
at a different height. It is to be borne in
mind that it is this keeper-plate and its
engagement with the matrices that deter-
45 mines the vertical position of the latter, and
consequently the location of the characters
with reference to the two sides or edges of
the slug. A line of matrices is commonly
50 supported in a vertically movable carrier,
known as the first elevator, by which the line
is lowered at the proper level in front of the
mold, after which the mold and the keeper
advance against the edges of the matrices to
55 engage therewith. Whenever a change is
made in the font of matrices, or in the thick-
ness of the slugs produced, it is necessary
that the keeper shall be adjusted vertically

and that the movement of the elevator which
presents the matrices shall be varied to corre-
spond, as otherwise the ears of the matrices
would fail to properly engage beneath the
shoulder of the keeper, and would be in
danger of mutilation thereby.

It is the aim of the present invention to
insure the proper and automatic control of
the elevator with reference to the location of
the keeper, and to this end it consists broadly
65 in the employment of intermediate or coöp-
erating parts, by which the location of the
keeper and the movement of the elevator, or
other mechanism for presenting the line to
the mold, may be made dependent one upon
70 the other.

In the accompanying drawings I have
shown my invention applied to a commercial
Mergenthaler machine of the present day,
the drawings being limited to those parts
75 with which the improvement is immediately
associated. As to all other parts, the ma-
chine may be of any ordinary or approved
construction.

Figure 1 is a perspective view of the second
elevator, the top of the vise-frame, the mold,
and adjacent parts, with my devices applied
thereto, the elevator being in its uppermost
80 position. Fig. 2 is a vertical section from
front to rear through the center of the parts
85 shown in the preceding figure, the elevator
being lowered and the matrix line presented
to the mold in casting position.

Referring to the drawings, A represents
the main-frame, and B the mold containing
90 the slot or mold proper b, in which the slugs
are cast. This mold may be mounted as
usual, on a vertical supporting-wheel or disk
b', having an intermitting rotary motion and
also a motion forward and backward face-
95 wise of the mold, as in the ordinary Mergen-
thalier machines.

C represent the so-called keeper-plate se-
cured to the face of the mold and having one
or more longitudinal shoulders c parallel with
100 the mold-slot, to engage the matrices and
hold their characters in exact alinement in
front of the mold.

D, D, are the matrices of the form usually
employed in Mergenthaler machines, with
105 the letter or matrix proper in one edge, and
with the protruding ears or shoulders above
and below the character, so that when the
matrices are assembled in line in front of the
mold, their lower ears, on the operative side, 110

will be engaged beneath the shoulder on the keeper-plate, as plainly shown in Fig. 2.

E represents the vertically movable support commonly known as the first elevator, in which the composed line of matrices is suspended, and by which the line is lowered to the casting level in front of the mold.

During the descent of the line, the mold stands in its rearmost position in order to 10 avoid interference with the descending matrices. After the elevator E and the contained matrices are lowered, the mold is advanced until the keeper engages over the matrix ears in the manner shown, after 15 which the elevator E is urged upward to lift the matrices and seat the upper surfaces of the alining shoulder on the keeper-plate, whereby all the characters in the line are brought to exact alinement horizontally, as 20 usual in Mergenthaler machines.

It will be observed that the vertical position of the matrix characters in relation to the mold, is determined by the keeper, which is adjustable vertically on the mold. By 25 raising or lowering the keeper, the entire line of matrices will be raised or lowered, and their characters caused to assume higher or lower positions in relation to the mold, so that the type characters will be cast centrally along the slug, or near the upper or lower edge, as demanded; and this regardless of the thickness of the slug, which may be varied by the usual adjustment of the 30 mold.

The keeper may be secured and adjusted by any suitable means, for example, by the horizontal slide c' seated in the mold and provided with a groove to receive an oblique or diagonal rib on the back of the keeper, as 35 fully explained in U. S. Patent No. 846,053.

It is important that the elevator E shall be arrested in its descent at such point that the shoulder of the advancing mold may pass over the matrix ears, and that it shall be prevented 40 from stopping in such position that the shoulder of the keeper will contact with and mutilate the ends of the ears. For this purpose, a stop-screw F is mounted in the elevator E, to contact with the solid part of the 45 machine and arrest its descent. Heretofore this screw has been arranged to seat itself on top of the main-frame. As however, the keeper-plate is adjustable in relation to the mold, it is necessary that the elevator and 50 matrices shall be arrested in their descent at points corresponding with the position of the keeper, whatever it may be, and it is to this end that my invention is chiefly directed. For this purpose, I mount on top of the main- 55 frame a horizontal slide G, having at one end a series of steps g at different heights and in such position that one or another of these steps may be brought beneath the stop-screw F by moving the slide endwise so that the 60 elevator and the matrices will be arrested in 55

one position or another, according to the slide and to the particular step which is brought under the stop-screw.

In order that the stop-slide may be automatically adjusted to correspond with the 70 position of the keeper, I propose to connect them by any suitable intermediate devices, so that the position of one will determine the operative position of the other. In the drawings I have shown for the purpose, a lever H, pivoted to the frame and connected at the lower end with the stop-slide G, and also a second lever I, pivoted to the elevator E, its 75 form and arrangement being such that when the elevator is lowered, one end of the lever I will contact with the end of the keeper C, while the other end contacts with the lever H.

As the elevator completes its descent, the lever I, contacting with the keeper, is caused to swing about its axis so that it in turn operates the lever H and advances the stop-slide 80 G to the proper position.

In Fig. 1, the elevator and its lever are shown in their elevated positions. The dotted lines indicate the downward course of the 90 lever with the elevator and the points at which its two ends contact respectively with the keeper and the lever H.

It will be observed that under the above arrangement, the height of the keeper C determines the extent of movement of the lever I and the distance which the slide G is advanced. In other words, the keeper determines, through the intermediate parts, the 95 height of the stop-shoulder presented to arrest the descent of the elevator and matrices. 100

In all linotype machines, a safety device is provided to prevent the machine from being started if the elevator E fails to descend to the proper point. This device consists of a 105 vertically and laterally movable rod J seated in the frame and connected at the lower end with clutch-controlling devices, while the upper end is arranged in the path of a screw or projection j on the vise, so that the vise in 110 descending will depress the rod J. Unless the vise descends to the proper level and depresses the rod J a corresponding distance, the machine is prevented from starting, in a manner well understood in the art.

As my mechanism contemplates the arrest of the vise at different levels, it is necessary to provide a compensating device which will move the stop-rod J a corresponding distance. For this purpose I provide the stop-slide G with a second stepped member g' connected thereto by a horizontal pivot and arranged to pass between the upper end of the rod J and the screw j so that the thickness presented between these members will correspond with the level at which the elevator is arrested. If the elevator stops at a high level, the thick portion of the member g' will be presented. If, on the other hand, the elevator descends to a lower level, the thinner 115 120 125 130

portion will be presented, and thus the variation in the height of the elevator is automatically compensated for in such manner as to insure the proper and automatic action of the clutch-controlling devices.

While I have shown my improvement as embodied in a Mergenthaler or line-casting machine commonly known under the trade mark "Linotype", and in the form which I deem best adapted for general use, it is to be understood that it may be embodied in various equivalent forms having a similar mode of action, and that it may be embodied in all machines containing means for adjusting the matrices transversely of the mold slot.

The essence of the invention lies in so connecting or arranging the means which present the matrices to the mold, and the means which determine the adjustment of the characters in relation to the mold-slot, that they must receive corresponding adjustments.

While the stop with steps is believed to be more simple and cheaper than any other, it will of course be understood that it may be replaced by any form of stop adjustable or variable in height provided it is operated automatically.

Having described my invention, I claim and desire to secure by Letters Patent,—

1. In a line-casting machine, the combination of a mold, matrices, means for presenting the matrices in front of the mold, means for determining the longitudinal adjustment of the matrices in relation to the mold, and intermediate means to insure corresponding adjustments in the presenting and alining devices.

2. In a line-casting machine, the combination of a mold, matrices coöperating therewith, means for presenting the matrices to the mold, an adjustable keeper - plate to aline the matrices in relation to the mold, and means controlled by the keeper - plate and acting in turn to control the matrix-presenting means.

3. In combination, a mold B, an adjustable keeper-plate C, a movable matrix-carrier E, and a stop for said carrier controlled by the keeper.

4. As an improvement in Mergenthaler machines, the movable mold B, the keeper C

adjustable thereon, the matrices adapted to engage the keeper, the matrix-elevator or carrier E, a stepped stop G to limit the movement of the elevator, and means whereby the keeper adjusts the stop.

5. The mold, the adjustable keeper, and the matrix-elevator E, in combination with the stepped stop for the elevator, and the levers H and I through which the stop is actuated from the keeper.

6. In a line-casting machine, the combination of means for presenting matrices to a mold, adjustable means for determining the longitudinal adjustment of the matrices in relation to the mold, means actuated by the line-presenting means to control the machine-driving connections, and means controlled by the matrix-adjusting devices and acting in turn to determine the time at which the line-presenting devices actuate the driving connections.

7. In a line-casting machine, an adjustable keeper C to control the position of the matrices in front of the mold, a member J to automatically control the machine-driving connections, and intermediate devices, whereby the position of the keeper C determines the time at which the member J is actuated.

8. In combination with the matrix-elevator E and the clutch-controlling member J, a movable stop g to arrest the elevator in different positions, and a member g' jointed thereto and acting on the member J.

9. In a line-casting machine, and in combination, with an elevator E for presenting the matrices to the mold, a member J controlling the machine-driving connections, adjustable means to determine the alinement of the matrices in front of the mold, and automatic devices controlled by the alining device and acting in turn to limit the movement of the elevator E and to determine the time of action of the driving connections.

In testimony whereof I hereunto set my hand this eleventh day of January, 1908, in the presence of two attesting witnesses.

JOHN R. ROGERS.
